UNITED STATES PATENT OFFICE.

JOHN T. DUFF, OF PITTSBURG, PENNSYLVANIA, ASSIGNOR TO A. M. DUFF,
A. M. NEGLEY, AND H. G. HUGUS, ALL OF SAME PLACE.

MACHINE FOR GRINDING AND POLISHING THE EXTERNAL SURFACES OF HOLLOW WARE.

SPECIFICATION forming part of Letters Patent No. 369,327, dated September 6, 1887.

Application filed November 11, 1886. Serial No. 218,644. (No model.)

To all whom it may concern:

Be it known that I, JOHN T. DUFF, a citizen of the United States, residing at Pittsburg, in the county of Allegheny and State of Pennsylvania, have invented certain new and useful Improvements in Machines for Grinding and Polishing the External Surface of Hollow Ware; and I do hereby declare the following to be a full, clear, and exact description of the invention, such as will enable others skilled in the art to which it pertains to make and use the same, reference being had to the annexed drawings, which form a part of this specification.

15 My invention relates to a machine for grinding and polishing the exterior surface of hollow ware, the object being to provide a machine that will grind and polish the outside of any size or form of hollow ware; and it consists in a means for securing the object in position and a device whereby a grinding-wheel in rapid motion may reach all points of the surface to be polished, together with various other details of construction and combination 25 of parts, as will be fully set forth hereinafter, and pointed out in the claims.

In the annexed drawings, Figure 1 is a front elevation of my improved exterior grinding and polishing apparatus constructed in accordance with my invention. Fig. 2 is a plan view of the same.

To put my invention into practice I provide a strong metal standard, 1, and secure the same to one end of a bed-plate, 2, by a suitable number of bolts, 3. Across the top of this standard 1, in the direction of the length of the machine, I arrange in suitable bearings, 4, a strong shaft, 5, having attached to one end a cylindrical form or holder, 6, of a form corresponding 40 to the contour of the inner surface of the vessel to be ground or polished. Between the bearings 4 of this shaft 5 I secure a driving-pulley, 7, of small diameter, which affords a means for rotating the shaft. To the front of 45 this standard 1, I place a sliding carriage, 8, capable of moving along a frame, 9, (attached by suitable brackets, 10, to the standard 1,) by means of a rack, 11, formed on the under side of the carriage 8, engaging with a pinion, 12, 50 mounted on a shaft, 13, and operated by a hand-

wheel, 14. On the upper surface of this carriage 8, I secure a table, 15, and arrange the same in suitable slides, which will allow a limited movement at right angles to that of the carriage 8 below. The table 15 may be 55 moved back and forth by a screw-shaft, 32, working in lugs 34 on the carriage 8, and operated by a hand-wheel, 33.

On the top of the table 15, I pivot an annular plate, 16, and secure the same thereto by 60 set-screws 17, operating in circumferential slots 18, which will admit of the plate revolving horizontally a short distance about its pivotal point. Across the top of this annular plate 16, I secure, in proper bearings, 19, a shaft, 20, 65 having attached to one end thereof a large grinding-wheel, 21. Between the bearings 19, I attach to the shaft 20 a tight and loose pulley, 22, which, in connection with suitable overhead belt-pulleys, gives the shaft 20 a rapid 70 rotation on its axis. At the front of the cylindrical holder 6, and in a direct line therewith, I erect another standard, 23, and secure the same to the base-plate in the same manner, as before described. On the top of this standard 75 23, I construct a frame, 24, having suitable slides formed on the top of the same, in which I arrange a moving table or carriage, 25, and operate the same by a rack, 26, formed on the under side, a small toothed wheel attached to 80 a transverse shaft, 27, and a hand-wheel, 28, as in the carriage 8, before described. To this shaft 27, I secure a suitable clutch, 29, which engages with another formed on the side of the frame 24, and serves to lock the carriage 25 at 85 any desired position. On the top of this sliding carriage 25, I arrange in proper bearings, 31, a shaft, 35, having an enlarged end or cap, 30, nearest the holder 6.

In operation the vessel to be ground and 90 polished is placed over the holder 6, fitting neatly about the same. The carriage 25, conveying the shaft 29 and cap 30, is brought forward by means of the hand-wheel 28 and pinion operating in the rack 26, which operation 95 tightly clamps the vessel to the holder 6. The clutch 29 is now engaged, which retains the carriage 25 in that position. The holder 6 and grinding-wheel 21 are put in rapid motion in opposite or reverse directions. By means of 100

the hand-wheel 14 the carriage 8 and grinding-wheel 21 are slowly moved down the side of the vessel until the lower edge is reached, at which time the annular plate 16 is revolved, 5 and thereby grinding around the corner to the edge of the clamping disk 30, which operation finishes the article. The clutch 29 is now released, the carriages 8 and 25 moved back by the hand-wheels 14 and 28, respectively, and 10 the vessel removed.

The objects of the upper carriage or table, 15, are to take up the wear or wasting of the grinding-wheel 21 by moving the same toward the work, and also to afford a means of grinding articles of large and small diameters. 15

Having described my invention, what I claim is—

1. The combination of the supporting frame, the grinder, the rotatable holder mounted in 20 fixed bearings in said frame, and an adjustable clamping device consisting of the combination of the carriage 25, the headed shaft 35, having

bearings in said carriage, the rack, pinion, and hand-wheel for moving the carriage toward and from the holder, and the clutch for locking the carriage in position, substantially as set forth. 25

2. The combination of the supporting-frame, the rotatable holder mounted in bearings in 30 said frame, the adjustable clamping device arranged opposite the end of the holder, the grinding-wheel, its carriage, the guideways or tracks running parallel with the axis of the holder and by the side thereof, in which the carriage moves, the transverse guideways in 35 which the carriage moves toward and from the holder, and the adjustable bearings for the grinder for tilting or varying the angle of the grinder relatively to the holder, substantially as set forth.

JOHN T. DUFF.
